UNITED STATES PATENT OFFICE.

OMER GUITTARD, OF SAN FRANCISCO, CALIFORNIA.

GLOVE.

SPECIFICATION forming part of Letters Patent No. 237,011, dated January 25, 1881.

Application filed May 24, 1880. (Model.)

To all whom it may concern:

Be it known that I, OMER GUITTARD, of San Francisco, California, have invented a new and Improved Glove, of which the following is a specification.

My invention relates to an improved shape given to the blanks, or the pattern by which the skin or leather is cut to form the different parts of a glove before being sewed together; 10 by which improvement, first, great economy of material is effected; second, the seams of the glove are brought in such a position as to be the least objectionable to the wearer; third, the glove is made stronger and more 15 serviceable, especially in gloves subject to hard usage, as in the case of driving and working gloves.

In the accompanying drawings I show the outlines of the patterns of the four pieces forming the glove, and also two views of the glove sewed together, one view of the palm side and one view of the back side.

Figure 1 outlines the pattern of the palm and back of the glove with the back side of all the fingers and the palm side of the first and fourth. Fig. 2 outlines the pattern for the thumb-pieces. Fig. 3 outlines the pattern for the palm side and sides of the second finger. Fig. 4 outlines the pattern for the palm side and sides of the third finger. Fig. 5 is the palm view of the glove sewed together. Fig. 6 is the back view of same.

In the pattern shown by Fig. 1, A is the palm side of fourth finger. B is the palm side of first finger. C is the back side of first finger, D of the second, E of the third, and F of the fourth. G is the hole for the thumb to

pass through, and H is a flap-piece, left to sew against the inside of the thumb to reinforce the glove in the crotch between the 40 thumb and first finger. I in Fig. 5 marks where the seam comes upon the second and third fingers.

In forming a glove after the patterns shown it will be found that none of the seams come 45 either on the palm side or between the fingers—a very good point in either heavy skin working-gloves or in dress-gloves, as there is much discomfort in having the seams come between the fingers—and when the seams are made on 50 the palm side the glove has a stiff unyielding feeling.

The flap-piece H is of great benefit in reinforcing the seam at a point very liable to rip open either in working, driving, or dress 55 gloves.

The gloves made after my plan may of course be bound and finished off in any suitable style and made of the usual materials employed in glove-making.

What I claim as my invention, and desire to secure by Letters Patent, is as follows:

A glove formed of the four parts or blanks 1, 2, 3, and 4, sewed together, blank 1 forming the palm side and back of glove, with the 65 back of the four fingers and palm side of first and fourth fingers, blank 2 forming complete thumb, and blanks 3 and 4 forming palm and side of second and third fingers, all substantially as herein described and shown.

OMER GUITTARD.
